DESIGN FOR AN APRON

Ada Quinn, Ogden, Utah

Application July 20, 1935, Serial No. 57,767

Term of patent 7 years

To all whom it may concern:

Be it known that I, Ada Quinn, a citizen of the United States, residing at Ogden, in the county of Weber and State of Utah, have invented a new, original, and ornamental Design for Aprons, of which the following is a specification, reference being had to the accompanying drawing, forming part thereof.

The design resides in an apron made of contrasting materials, with a special design with relation to the side extensions and back of the apron.

I claim:

The ornamental design for an apron, as shown and described.

ADA QUINN.
